AIR FIELD GROUND LIGHT

Johannes Bernardus de Boer, Eindhoven, Netherlands, assignor to Hartford National Bank and Trust Company, Hartford, Conn., as trustee

Application September 4, 1952, Serial No. 307,767

Claims priority, application Netherlands October 4, 1951

1 Claim. (Cl. 240—1.2)

This invention relates to ground lights and more particularly to ground lights for air fields.

The term "ground light" is to be understood to mean a light fitting for use on air fields for indicating runways, obstacles and the like, comprising a base which is sunk into the ground in such manner that its upper surface is located at the level of the field. Other lights which are erected almost completely above the ground level of airfields are not included in the term "ground lights."

As a rule, a ground light is constituted by a base, an electric lamp holder, a light source and an optical system beaming rays of the light source in the desired manner. It is evident that, as an alternative, more than one lamp holder, light source and optical system may be combined in one ground light.

The object of the invention is to provide a construction for a ground light having a very compact structure.

The ground lights hitherto used were constructed so that at least the lamp holder and the lamp were arranged inside the base below ground level. The invention, however, is based on the recognition of the fact that a lamp is comparatively inexpensive, so that its destruction is in general less disadvantageous than the destruction of the known assembly, while the construction of the base may be much lighter in weight and less voluminous if the lamp is not arranged inside the base.

According to the invention a ground light is characterized in that the base contains solely a lamp holder with current supply members, whereas the envelope of the light source or sources and the optical system or systems are positioned above the base.

The light source may be provided with a separate optical system, or an envelope of the light source itself may constitute the optical system. For example, an incandescent lamp may be used in which part of the bulb is a reflecting surface.

In order to obtain an inexpensive construction for a lamp holder and avoid the risk of water penetrating into the fitting, in one embodiment a watertight sealing means, for example, a rubber ring, is provided between the lamp cap of a light source and the base. Said rubber ring prevents water from penetrating to the contacts of the lamp holder and is preferably located under the upper surface of the base, so that it is not damaged in case of a collision which would destroy the lamp and the optical system. Despite the destruction of the lamp and the optical system, the

2

interior of the base remains protected against the penetration of moisture.

In order that the invention may be readily carried into effect, it will now be described in greater detail with reference to one embodiment shown, by way of example, in the accompanying drawing in which:

The figure is a sectional view of a ground light according to the invention.

The ground light is constituted by a receptacle 1, which may be made of cast iron. Said receptacle may be dug directly into the ground, but in most cases it should first be secured in a block of cement or concrete which is sunk in the ground.

The receptacle comprises a cavity 2, which is closed by a disc 3. The latter is urged by a plurality of screws 4 on a rubber sealing ring 5. The receptacle together with the disc and sealing ring constitute the base of the fitting. The disc 3 comprises an aperture into which a lamp holder 6 is inserted from the bottom and fixed in position with the use of screws 7. A current supply cable 8 connected to the lamp holder is led in through an aperture of the base which is sealed by a tightening nut 9 and a rubber ring 10. An incandescent lamp 11 is placed in the holder 6, a rubber ring 13 for sealing being provided between the lamp cap 12 and disc 3 and lamp holder 6.

A silver-plated part 14 of the bulb of the incandescent lamp is in this case shaped in such manner as to provide the desired beaming of the light. In addition the bulb is provided with a hood 15 which is manufactured from, for example, thin sheet metal and which prevents unwanted stray of the light.

The figure shows that in case of a collision the cap 15 and the lamp 11 will be destroyed, but that there is no risk of moisture penetrating to the interior of the base 1, since the lamp cap 12 will not allow the passage of water and the penetration of moisture along the lamp cap is prevented by the rubber ring 13.

It is evident that many variations in the form and construction of the parts above the ground are possible.

40 What I claim is:

A ground light of the type used on an airfield consisting of a receptacle, an apertured closure member in said receptacle, means removably securing said closure member in said receptacle, a lamp holder in said aperture, a lamp bulb in said holder, a reflector on said bulb, all elements of said ground light being positioned below ground level with the exception of said lamp bulb and reflector whereby when said ground light is struck by a portion of an airplane only the lamp bulb and reflector are damaged.
